CRUTCH

James F. Wilson, Des Moines, Iowa, assignor of
forty-nine per cent to Walter E. Baker, Des
Moines, Iowa

Application June 11, 1941, Serial No. 397,578

3 Claims. (Cl. 135—49)

My invention relates to the art of crutches, particularly the class having cushioning springs.

The object of my invention is to provide a crutch of this class of simple, durable and inexpensive construction.

A further object is to provide a crutch which may be readily, quickly and easily adjusted as to the weight and height of the user, and the length of the user's arm.

In the accompanying drawing—

Figure 1 shows a side elevation of the complete crutch;

Figure 2 shows an enlarged longitudinal sectional view of the upper portion of the crutch;

Figure 3 shows a side view, partly in section, of the lower end portion of the crutch;

Figure 4 shows a detail sectional view on the line 4—4 of Figure 1; and

Figure 5 shows a detail sectional view on the line 5—5 of Figure 1.

The body of the crutch is formed of a metal tube 10 of uniform diameter. At about the central portion of the tube 10 is a metal socket 11, open at its top and riveted in position. The top of the tube is interiorly screw threaded at 12, and a tubular nut 13 is inserted therein. This nut has a hexagonal head 14 resting upon the top of the tube. At its lower end the tube 10 is screw threaded on its exterior and an extension body portion 15 is provided with an internal screw thread to receive the lower end of the tube 10. At the lower end of the part 15 is a rubber tip 16.

The upper portion of the crutch is also formed of a metal tube 17 slidably fitted into the nut 13 and the socket 11. At its top is a metal arm rest 18, and below the nut 13 a collar 19 is riveted to the tube 17 and is slidably mounted in the upper end of the tube 10. A rubber tip 17a is fixed to its lower end.

An extensible coil spring 20 is inserted between the tubes 10 and 17 and engages the socket 11 and the collar 19.

The crutch handle 21 is formed with a collar 22 surrounding the tube 10 and is secured to the tube 10 by a screw 23. A series of openings 24 is formed in the tube 10 through which the screw 23 may be extended and whereby the handle may be positioned at any desirable distance from the arm rest.

In practice, I have demonstrated that the entire crutch with the exception of the extension 15 and the spring 20 may be made of the same size and length for users of various heights and weights. If the weight of the user is relatively heavy, a stiff spring is used, and the length of the crutch may easily be changed by adding

an extension member of the proper length. Also, the position of the handle may be readily and easily adjusted.

To remove and replace a spring it is only necessary to unscrew the nut 13, then the tube 17 can be removed and a spring of different resiliency may be inserted and the nut replaced.

A merchant selling my crutch need have on hand only a limited number of crutches and a larger number of springs of various degrees of resiliency and a larger number of extension tubes. When supplying a crutch for a customer the crutch may be easily and quickly adapted to the weight, height and arm length of the customer by inserting a proper spring and extension tube, and adjusting the handle.

I claim as my invention:

1. In a crutch, the combination of a tubular metal body portion interiorly screw threaded at its upper end, a tubular nut inserted in said screw-threaded portion, a socket open at its upper end fixed to the interior of the tube, an upper crutch member of smaller diameter than the body portion extended through the nut and into the socket and having a collar fixed thereto to engage the nut, and an extensible coil spring surrounding the upper crutch member and engaging said socket and said collar.

2. In a crutch, the combination of a tubular metal body portion interiorly screw threaded at its upper end, a tubular nut inserted in said screw-threaded portion, a socket open at its upper end fixed to the interior of the tube, an upper crutch member of smaller diameter than the body portion extended through the nut and into the socket and having a collar fixed thereto to engage the nut, an extensible coil spring surrounding the upper crutch member and engaging said socket and said collar, and an elastic cushioning tip fixed to the lower end of the upper crutch member and engaging the bottom of the socket when the spring is fully compressed.

3. In a crutch, the combination of a tubular metal body having an interiorly screw-threaded portion, a tubular nut inserted in said screw-threaded portion, a tubular socket fixed in position within the body portion and having its open end extended toward said nut, a crutch member of smaller diameter than said body portion extended through said tubular nut and into said socket and having a collar fixed thereto to be engaged by said nut, an extensible coil spring surrounding said smaller crutch member and engaging the open end of the socket and said collar.

JAMES F. WILSON.
